UNITED STATES PATENT OFFICE.

OSCAR TACK, OF NEWARK, NEW JERSEY, ASSIGNOR TO TOWER & LYON COMPANY, OF NEW YORK, N. Y., A CORPORATION OF NEW YORK.

BORING-TOOL.

No. 884,111.

Specification of Letters Patent.

Patented April 7, 1908.

Application filed August 12, 1905. Serial No. 273,857.

To all whom it may concern:

Be it known that I, OSCAR TACK, residing at Newark, in the county of Essex and State of New Jersey, have invented certain new and useful Improvements in Boring-Tools, of which the following is a full, clear, and exact description, such as will enable others skilled in the art to which it appertains to make and use the same:

10 My invention relates to boring tools and, in a more specific relation thereof, to expansion or expansible bits adapted for boring wood.

15 One of the objects contemplated is the provision of a tool of the class described which shall be characterized by ease of manipulation in operation.

20 Another and more specific object is the prevention of crowding or dragging the material being cut during the operation of the tool, and the attainment of an efficient shearing cut without impairing the general efficiency of the tool.

25 The invention accordingly consists in the features of construction, combinations of elements and arrangement of parts which will be exemplified in the device hereinafter described and the scope of the application of which will be indicated in the following 30 claims.

In the accompanying drawing, wherein is shown the preferred embodiment of my invention, Figure 1 is a front elevation, Fig. 2 is a side elevation, Fig. 3 is a bottom plan 35 view, Fig. 4 is a perspective of the expansible cutter.

Similar reference characters refer to similar parts throughout the several views of the drawing.

40 In order to more clearly understand the character of my invention, it should be noted that tools of the general class described have a tendency to crowd or bind during operation, and the chips being severed tend to become 45 wedged, with the result that the parts of the bit are liable to frequent displacement. When the main cutting edge of an adjustable cutter is located either forward or rearward of an axial plane of the bit head, the 50 cutter is either forced or dragged, that is, it is either working ahead or behind the other elements of the tool. This increases the difficulty of operation and decreases the efficiency of the tool. More metal, proportionately, must accordingly be provided and the

expense of manufacture is correspondingly increased. The present invention, however, provides a construction which obviates the defects pointed out and accomplishes, among others, the objects indicated.

Referring now to Fig. 1, the illustrative embodiment of my invention is shown in operative position. To the bit shank 1 located below the bit head 2 is adjustably secured by wedge plate 3 an adjustable cutter 4 having two edged spurs 5 and 6 mounted thereon. The spur 6 is ordinarily mounted upon the cutter at a point where it will provide for severing and dividing the chips to be cut by the cutter 4 so as to minimize any crowding or wedging and to insure their free discharge. A lead screw 7 is screw-threaded into the bit head. Plate 3 is held in engagement with the shank 1 of the cutter 4, as appears more clearly in Fig. 2, by any suitable means, as a screw 8. A projection or lug 9 (Fig. 1) upon the plate 3 is adapted to register and engage with a notch 10 in the shank, to prevent relative lateral movement between the said plate and shank and thus prevent the possibility of displacement of the cutter 4 while the various members are loose and being adjusted or tightened.

Referring now to Fig. 3, the relative arrangement of parts desired for the attainment of certain of the objects contemplated by my invention, is illustrated. The main cutting edge *b* of the cutter 4 is shown in an axial plane of the bit head 2. The point *c* of the cutting lip 11 on the bit head 2 is preferably located in the same plane and the lower cutting point *d* (Fig. 4) of the spur 5 is likewise preferably located therein. A portion of the periphery of the bit head 2 is cut away to form a notch 13 as a channel for chips and, when the cutter 4 is positioned so that the bit will cut a relatively small hole, to accommodate and form a protection and enclosure for the spur 6. The usual spur 12 may, if desired, be located upon the bit 100 head 2.

Although the use of the construction herein disclosed is believed to be sufficiently apparent, a general statement of the manner of use, taken in connection with certain of the purposes and advantages contemplated and attained, as well as of the disadvantages overcome, may be made.

When the bit is being operated, it will be seen, considering Fig. 3 of the drawing, that

if the main cutting edge of the cutter were located either forward or rearward of an axial plane of the bit head, the revolution of the latter in operation would produce either

- 5 an extreme shearing cut, or a driving cut. By locating the main cutting edge of the adjustable cutter in an axial plane of the bit head the cutter does not work ahead of nor out of unison with the other parts of the bit.
- 10 This arrangement produces a normal shearing cut which is much more efficient than the usual extreme shearing or driving cut. The outer spur upon the cutter having its lowermost or extreme cutting point in an axial plane, severs the wood to be removed at the same time the wood which has been cut by said spur is being cut by the main cutting edge of the cutter. The spur 6 mounted upon the cutter between the working extremity thereof and the periphery of the bit head divides the chip to be loosened, and thus minimizes the tendency to wedge. This feature of locating the principal cutting edges and points in an axial plane of the bit head results in a construction wherein all the parts work in uniformity with each other and are subjected to a minimum strain. This results in easier manipulation, less liability of the parts to get out of placement, and the 30 possibility of producing an efficient tool of the class described from relatively less metal.

Where the expression "main cutting edge" is used, it is intended to comprehend the working edge of the adjustable cutter extending from the periphery of the bit head to a point near the spur 5 where good shop practice would make it necessary to curve the cutting edge of the cutter to meet the cutting edge of the spur.

40 It will accordingly be seen that the present invention provides a construction which attains, among others, the objects and advantages herein specified and obviates the defects and objections indicated.

45 The fact, which is particularly applicable to constructions of this general character, should be obvious, that various changes in detail and in construction and formation of parts, may be made; that elements which apparently vary from those specified herein may be substituted and other changes made in the construction illustrated, which, while materially changing the appearance thereof, would still involve the ideas and appropriate 55 the utilities suggested by the invention disclosed herein.

I desire it also to be understood that the language used in the following claims is intended to cover all of the generic and specific features of the invention herein described and all statements of the scope of the invention which, as a matter of language, might be said to fall therebetween.

Having described my invention, what I claim as new and desire to secure by Letters Patent, is:—

1. In an expansion bit, in combination, a bit head, an adjustable cutter mounted thereon, and a plurality of edged spurs depending from said cutter, one of said spurs being located rearward of the other thereof, and of the main cutting edge of said cutter, and between the cutting extremity of said cutter and the periphery of said bit head.

2. In an expansion bit, in combination, a bit head, an adjustable cutter mounted thereon, and a plurality of edged spurs depending from said cutter, one of said spurs being located rearward of the other thereof and of the main cutting edge of said cutter and between the cutting extremity of said cutter and the periphery of said bit head, the main cutting edge of said cutter being located in a diametric plane of said bit head.

3. In an expansion bit, in combination, a bit head, an adjustable cutter mounted thereon, and a plurality of edged spurs depending from said cutter, one of said spurs being located rearward of the main cutting edge of said cutter and between the cutting extremity of said cutter and the periphery of said bit head, the main cutting edge of said cutter being located in an axial plane of said bit head, a portion of the periphery of the latter being cut away opposite said latter spur to form a channel for chips.

4. In an expansion bit, in combination, a bit head, an adjustable cutter mounted thereon, and a plurality of edged spurs depending from said cutter, one of said spurs being located rearward of the main cutting edge of said cutter and between the cutting extremity of said cutter and the periphery of said bit head, a portion of the periphery of the latter being cut away opposite said latter spur to form a channel for chips.

In testimony whereof I affix my signature, in the presence of two witnesses.

OSCAR TACK.
